TAKE-UP FOR SEWING MACHINES

Sydney Zemis, Bridgeport, Conn., assignor to The
Singer Manufacturing Company, Elizabeth,
N. J., a corporation of New Jersey

Application October 12, 1937, Serial No. 168,553

36 Claims. (Cl. 112—248)

This invention relates to sewing machines and more particularly to sewing machine take-up mechanisms, and has for its objective the provision of an improved form of take-up mechanism for use with a high speed sewing machine and which will effectively control the thread during the stitch-forming cycle.

Another object of this invention is to provide means for preventing thread from winding about 10 the take-up elements.

With the above and other objects in view, as will hereinafter appear, the invention comprises the devices, combinations and arrangements of parts hereinafter set forth and illustrated in the 15 accompanying drawings of a preferred embodiment of the invention, from which the several features of the invention and the advantages attained thereby will be readily understood by those skilled in the art.

Fig. 1 is a rear side elevation of a sewing machine embodying my invention.

Fig. 2 is a top plan view of the machine shown in Fig. 1.

Figs. 3, 4, 5 and 6 are left end elevations of 25 the machine with the face plate removed, showing the position of the stitch-forming and thread-controlling elements at various points in the stitch-forming cycle.

Fig. 7 is a sectional view taken substantially 30 along the line 7—7 of Fig. 3.

In the selected embodiment of this invention, 10 represents the bed of the machine from which rises a standard 11 carrying an overhanging arm 12 terminating in a hollow head 13. Journaled 15 in the arm 12 is the usual needle-bar actuating shaft 14 (Fig. 2) which carries a pulley 15 and is driven by a balance-wheel 16 provided with a belt groove 16'.

Journaled in the bearings 17 and 18 carried 40 by the arm 12 and in rear of the needle-bar shaft 14 is a shaft 19 carrying a pulley 20 and journaled beneath the bed 10 is a hook-shaft 21 carrying a pulley 22. The pulleys 15, 20 and 22 are all operatively connected by a single belt 23 and 45 therefore the shafts 14, 19 and 21 all rotate in the same direction and at a uniform speed. The pulley 15 is twice as large as the other two pulleys and therefore the shaft 19 and hook-shaft 21 operate at twice the speed of the needle-bar 50 actuating shaft 14.

Journaled in the head 13 is a presser-bar 24 carrying a presser-foot 25 which cooperates with the usual four-motion feed-dog 26 to advance the work. The mechanism for imparting the four- 55 motion movement to the feed-dog is old and well

known and may be of any suitable form. Also journaled in the head 13 is a reciprocatory needle-bar 27 which is actuated from the shaft 14 by means of the conventional crank 29 and link 30 (Figs. 5 and 7). The needle-bar 27 carries a needle 28 which cooperates with a loop-taker 31 which may be of any suitable form.

Fixed to the end of the shaft 19 by a set-screw 32 (Fig. 7) is a hub 33 to which a disk 36 is secured by the screw 34 and shouldered stud 35 10 and the end of the shaft 19 is reduced to form, in effect, a second stud 37. Fixed to the disk 36 by the pins 38 is a second disk 39. It will be understood that the two disks 36 and 39 are spaced from each other by the washers 40 which 15 encircle the pins 38 and are carried by and rotate with the shaft 19.

Carried by the crank-pin 29 is a member 41 which is concentric with the shaft 14 and has secured thereto by the screw 41' a disk 42 which 20 carries by means of the pins 43 a second disk 44. The disks 42 and 44 are held spaced from each other by the washers 46. It is to be understood that the axis of rotation of the disks 42 and 44 25 is co-incident with the axis of the needle-bar shaft 14 and these disks rotate at the same speed as this shaft.

The thread T is led from the source of supply to a post 47, then to the ironing guide 48, adjustable tension 49, over the check-spring 50 and 30 under guide 51 then to the washers 40 and 46 carried by the disks and finally through the guides 52, 53 and then through the needle's eye.

It is to be understood that washers 40, 46 and 35 stud 35 engage the thread to control it and these elements are hereinafter termed thread-engaging 40 elements. It will also be understood that the washers 40 and 46 need not be used in pairs, as shown, but they may be of any suitable shape or size and one or more may be used with each take-up element. The number and shape would, of course, be determined by the thread requirements of the loop-taker.

The guide 51 is carried by a block 54 fixed to the presser-bar 24 so that when the presser-bar 45 is raised the guide 51 will move upwardly. The block 54 also carries an inverted U-shaped member 55 which is adapted to engage the usual pin 56 in order to release the tension on the needle-thread when the presser-foot is raised. It will 50 be understood that the presser-bar 24 and presser-foot 25 are urged against the feed-dog 26 by means of the flat spring 57 which has one end overlying the block 54 and its other end overlying a shouldered screw 58 carried by the 55

standard 11 of the machine. The spring 57 reacts against one end of the adjusting screw 59 and the usual lever 60 is provided for raising the presser-foot against the action of the spring.

5 Assuming the parts to be in the position shown in Fig. 3, the needle 28 has thrown out its thread-loop and the beak 62 of the hook is just entering the loop. At this point in the cycle there is a small amount of slack in the thread T.

10 In Fig. 4 the parts are shown at the point in the stitch-forming cycle just prior to the time when the needle-loop is cast off by the loop-taker. It will be observed, from a comparison of Figs. 3 and 4, that from the loop-seizing point to the

15 cast-off point in the stitch-forming cycle the thread-engaging elements 46 have moved slightly more than one-fourth of a revolution and the thread-engaging elements 40 have moved a little more than one-half of a revolution. During this

20 period both thread-engaging elements were giving up thread to the hook. In Figure 4 the stud or thread-engaging element 37 has engaged the needle-thread to prevent slack in the needle-thread between the guide 51 and guide 52 thereby

25 keeping the thread under control and preventing it from "whipping" about. The stud or thread-engaging element 35 has also engaged the needle-thread and as the element 35 is moving away from the element 46 the combined action is to place a tension on the thread and cause it to slip forward from the beak of the hook.

30 In Fig. 5 the stitch-setting point in the cycle is shown. When the mechanism moves from the position shown in Fig. 4 to that shown in Fig. 5 both of the thread-engaging elements 40 and 46 act to pull up the needle-loop and set the stitch. It will be noted that at the final stitch-setting point the thread-engaging elements are acting conjointly to give a gentle stitch-setting pull on the thread.

40 Fig. 6 shows the position of the parts of the mechanism immediately after the needle-point has entered the material for the succeeding stitch. In this view it will be noted that the 45 slack needle-thread is between the guide 51 and the thread-engaging elements on the smaller or rear take-up member. This is due to the fact that the thread-engaging elements operate in a counterclockwise direction thereby causing the 50 friction between the thread-engaging elements and the needle-thread to pull the thread away from the needle's eye. This is a distinct advantage in that it prevents loops of loose needle-thread from being thrown in front of and about 55 the needle. A guard 63 is fixed to the head of the machine by the screws 64 and is formed with a slot 65 (Fig. 1) which facilitates the threading of the take-up.

60 It has been found that if the needle-thread should, for any reason, break during the operation of the machine, the loose end may be accidentally caught or the thread may be looped about one of the thread-engaging elements, and, as the machine is operating at high speed, the 65 thread is wound about and hopelessly entangled in the operating parts of the take-up before the machine can be brought to rest. To overcome this difficulty the disk 36 is formed with a shallow groove 66 (Fig. 7) and to the guard 63 there 70 is secured a member 67 having a bent over and sharpened portion 68 which extends into the groove 66. It will be noted that the bent-over portion 68 is within the circle described by the movement of the element 40 and that it is 75 placed from the axis of movement of the ele-

ment. This, of course, causes the thread-engaging elements to move towards and away from the portion 68. Therefore if the thread should break and the free end is not thrown out by the centrifugal action of the rotating elements, the 5 thread is wound between the portion 68 of the member 67 and the take-up elements and after a few turns the friction between the loops of thread becomes sufficient to cause the thread to break or be severed.

10 Any complicated curve may be said to be composed of a series of simple harmonic curves. Therefore the complicated thread requirements of a sewing machine loop-taker may be satisfied by combining a series of thread-engaging elements which act conjointly or in series on the thread and are caused to execute simple harmonic motions and which engage the thread for periods of different duration during each stitch-forming cycle. From the foregoing description 20 it will be obvious that the thread-engaging elements 46, 40 and 35 are actuated at a uniform velocity and the duration of the engagement of the thread by these elements is different for each element. It will also be observed that the thread 25 is led to the thread-engaging elements in series and is acted on by these elements conjointly so as to satisfy the thread requirements of the loop-taker.

30 It will be obvious that the distances of the 30 thread-engaging elements from their axes of operation may be varied according to the size and construction of the loop-taker and that any number of thread-engaging elements may be used and that they may be operated at different 35 frequencies than those shown herein.

35 From the foregoing description considered in connection with the accompanying drawings, the construction, manner of operation and several 40 advantages of my improved sewing machine will be clearly and fully understood. It is apparent that such a take-up mechanism has a wide variety of uses, and it will be understood that the form, construction and arrangement of the elements employed may be varied. Therefore, the 45 privilege is reserved of resorting to all such legitimate changes therein as may be fairly embodied within the spirit and scope of the appended claims.

45 It will also be obvious that the amount of 50 thread given up by the take-up depends on the relative position of the axis of the take-up elements, and also the positions of the thread-guides relative to each other and relative to the take-up elements. For instance, the thread-guide 52 may 55 be moved into the vertical plane of the needle-bar thereby varying the action of the take-up. Also the guide 51 which is carried by the presser-bar varies the action of the take-up elements when the presser-foot is slightly raised due to the 60 thickness of the work under the presser-foot. Further it will be understood that the timing of the elements may be varied and that one or all of the elements which engage the thread may be reciprocatory or vibratory.

65 Having thus set forth the nature of the invention, what I claim herein is:

70 1. A take-up for sewing machines comprising a plurality of cyclically operable take-up elements, and mechanism for rotating said elements about their axes, said mechanism including means for causing one of said elements to rotate at a different frequency from the other of said elements.

75 2. A take-up for sewing machines comprising

5 a plurality of rotary take-up elements operating substantially in the same plane, mechanism for actuating said elements at different frequencies and constant speeds and means for guiding a thread to said elements in series relation and in the plane of operation of said elements.

10 3. A take-up for sewing machines comprising a plurality of rotary take-up elements operable about fixed axes, means for actuating said elements at different frequencies and means to guide a thread to said elements in series relation and in the plane of operation of said elements.

15 4. A take-up for sewing machines comprising a plurality of rotary take-up elements operating about spaced axes, and means for actuating said elements at different frequencies.

20 5. A take-up for sewing machines comprising a plurality of rotary take-up elements operating about spaced axes and acting on the same thread, and means for actuating said elements at a uniform angular velocity.

25 6. A take-up for sewing machines comprising a plurality of rotary thread-engaging elements operable about fixed axes, and means for actuating said elements at different frequencies.

30 7. In a sewing machine, the combination with a reciprocating thread-carrying eye-pointed needle and a complementary hook which makes more than one complete rotation for each needle reciprocation, of a plurality of cyclically operable take-up devices for the thread of said needle and means to concomitantly actuate them at different frequencies during each stitch-forming cycle, each of said devices acting upon the thread during each of its cycles of operation.

35 8. In a sewing machine, the combination with a reciprocating thread-carrying needle, and a rotary hook making a plurality of rotations to one complete reciprocation of said needle, of a plurality of cyclically operable needle-thread take-up devices which act in series upon the thread throughout the stitch-forming cycle and means to operate said take-up devices at the frequencies of the needle and rotary-hook, respectively.

40 9. In a sewing machine, the combination with a reciprocating thread-carrying needle and a complementary loop-taker, of a plurality of cyclically operable rotary take-up elements operable about different axes, and means for actuating said elements at different frequencies.

45 10. In a sewing machine, the combination with a reciprocating thread-carrying needle and a complementary loop-taker, of a plurality of cyclically operable rotary take-up elements rotatable about different axes, and means for actuating said elements at different frequencies and at uniform angular velocities.

50 11. In a sewing machine having a reciprocating thread-carrying eye-pointed needle and a loop-taker coordinated therewith, the combination of a plurality of cyclically operable thread-engaging elements, and means operable during each needle reciprocation for imparting to one of said elements a cycle of operation on the thread of said needle having a certain period of duration and to the other of said elements a cycle of operation on said thread having a period of duration different from the period of duration of the other element, each of said elements engaging the needle-thread simultaneously and during each cycle of operation.

55 12. In a sewing machine having a reciprocating thread-carrying eye-pointed needle and a complementary loop-taker, the combination of a

plurality of rotary thread-engaging take-up elements, said elements being mounted for movement about spaced parallel axes, mechanism actuating said elements and means for preventing thread from winding about said elements.

60 13. A take-up for sewing machines comprising a plurality of rotary thread-engaging elements, mechanism for actuating said elements in differentially timed relationship, and means for preventing thread from winding about said elements if the thread should break during the operation of the machine.

15 14. A sewing machine having in combination a reciprocating eye-pointed needle, a loop-taker coordinated therewith to form stitches, a plurality of take-up elements, said elements acting on the thread simultaneously and conjointly and mechanism for actuating said elements in the same direction and in differentially timed relationship.

20 15. A sewing machine having in combination a reciprocating eye-pointed needle, a loop-taker coordinated therewith to form stitches, a plurality of rotary thread-engaging take-up elements, said elements being mounted for movement about spaced axes and operating upon the needle-thread, and means for rotating said elements in the same direction.

25 16. In a sewing machine, the combination with a reciprocating thread-carrying eye-pointed needle, and a rotary hook making a plurality of rotations for each reciprocation of the needle, of a plurality of rotary needle-thread take-up devices acting upon the thread in series, and separate means for actuating each of said devices.

30 17. A take-up for sewing machines comprising a plurality of rotary take-up elements, mechanism for simultaneously rotating said elements at different frequencies and means for preventing thread from winding about said elements if the thread should break during the operation of the machine.

35 18. In a sewing machine having a reciprocating thread-carrying needle and a rotary hook coordinated therewith and making more than one revolution for each reciprocation of the needle, the combination of a plurality of cyclically operable needle-thread take-up elements which act upon the needle-thread conjointly throughout the stitch-forming cycle, and means for actuating said elements at different frequencies during each needle reciprocation.

40 19. In a sewing machine, the combination with a reciprocating thread-carrying needle, and a rotary hook making a plurality of rotations for each reciprocation of the needle, of a plurality of rotary needle-thread take-up devices operable about spaced axes and in series on the thread.

45 20. A take-up for sewing machines comprising a plurality of take-up elements adapted to move in circular paths about fixed axes and act simultaneously on the same thread, mechanism for rotating one of said elements, and means for rotating the other of said elements at a speed different from the speed of the first mentioned element.

50 21. In a sewing machine, the combination with a reciprocating thread-carrying eye-pointed needle and a rotary hook cooperating therewith and making more than one complete rotation for each needle reciprocation, of a plurality of rotary take-up elements which act simultaneously on the needle-thread, mechanism for rotating one of said elements and means for rotating another of said elements at a speed different from the speed of the first mentioned element.

22. A sewing machine having, in combination, a plurality of shafts, means for rotating said shafts about their longitudinal axes, take-up elements carried by said shafts and means for operating said shafts at different speeds.
23. A sewing machine having in combination, a bed carrying a bracket-arm, a pair of shafts journaled in the bracket-arm, a hook actuating shaft journaled in the bed, take-up elements carried by the shafts journaled in the bracket-arm and mechanism for rotating the hook-actuating shaft and one of the shafts journaled in the bracket-arm at the same speed and the other of said shafts at a speed different from the speed of the other two shafts.
24. A sewing machine having, in combination, a rotary needle-bar actuating shaft, a take-up element carried by said shaft, a second shaft, a take-up element actuated by said second shaft and means for actuating said second shaft a plurality of times for each rotation of said needle-bar shaft.
25. A take-up for sewing machines comprising a plurality of circularly moving rotary take-up elements acting simultaneously on the same thread and operable in the same plane, and means for rotating said elements at different speeds.
26. A take-up for sewing machines including a pair of disks operable about different axes, a thread-engaging element carried by each disk, the element on one of said disks being spaced a greater distance from the axis of rotation of its disk than the distance the other element is spaced from the axis of rotation of its disk.
27. A take-up for lock-stitch sewing machines comprising two rotary shafts, mechanism for rotating one of said shafts twice for each rotation of the other of said shafts and a rotary circularly moving take-up element actuated by each of said shafts, said elements being arranged to control the needle-thread.
28. A take-up for lock-stitch sewing machines comprising two shafts, mechanism for actuating one of said shafts twice for each actuation of the other of said shafts, each of said shafts being actuated during each stitch-forming cycle and take-up elements carried by each of said shafts.
29. A sewing machine having, in combination, a plurality of shafts, take-up elements rigidly fixed to each of said shafts and acting upon the same thread during each stitch-forming cycle, said elements being operable in circular paths about fixed axes, and means for actuating said shafts at uniform angular velocity.
30. A thread take-up for sewing machines comprising a plurality of rotary take-up elements operable about axes and having fixed radii, and means for actuating said elements at different frequencies.

31. A sewing machine having, in combination, a thread-carrying reciprocating eye-pointed needle, a rotary hook cooperating with the needle and making more than one complete rotation for each needle reciprocation, a plurality of cyclically operable take-up elements at least one of which is rotary, and means for actuating said elements at different frequencies.

32. A sewing machine having, in combination, a thread-carrying reciprocating eye-pointed needle, a hook cooperating therewith and making a plurality of revolutions for each needle reciprocation, a plurality of cyclically operable take-up elements acting upon the needle-thread during each stitch-forming cycle, and mechanism for actuating said elements during each stitch-forming cycle and at the frequencies of the hook and needle, respectively.

33. A sewing machine having, in combination, a bracket-arm carrying a hollow head, a thread-carrying eye-pointed needle, a shaft journaled in said bracket-arm for actuating said needle, a coordinated loop-taker, a rotary take-up element actuated by said needle-actuating shaft, a take-up shaft journaled in said bracket-arm, means for actuating said shaft a plurality of times for each actuation of the needle, and a take-up element actuated by said shaft.

34. A sewing machine having in combination, a plurality of spaced apart needle-thread controlling elements, means for rotating said elements about a common axis, and a stationary thread breaking element carried by the sewing machine and having a portion which extends in the direction of the axis about which said elements rotate and located in the space between said elements.

35. A sewing machine having in combination a needle-thread controlling element, mechanism for rotating said element in an orbital path about an axis spaced from said element, a second needle-thread controlling element spaced from said first mentioned element, means for rotating said second element in an orbital path, and a stationary finger having a portion located in the space between said elements and within the orbit described by said first mentioned element and outside of the orbit described by said second mentioned element.

36. A sewing machine having in combination a needle-thread take-up element, a disk carrying said element, and formed with a groove, means for rotating said disk, and a stationary thread-finger carried by the machine and having its free end terminating in a bent over portion which extends into said groove, said bent over portion being disposed between the take-up element and the axis about which it rotates.
